2 SHEETS—SHEET 2.

UNITED STATES PATENT OFFICE.

ELIJAH BESS, OF DEAN, MONTANA.

AUTOMATIC TRAIN-STOP.

1,286,510.

Specification of Letters Patent.

Patented Dec. 3, 1918.

Application filed September 24, 1917. Serial No. 192,984.

To all whom it may concern:

Be it known that I, ELIJAH BESS, a citizen of the United States, residing at Dean, in the county of Stillwater and State of 5 Montana, have invented certain new and useful Improvements in Automatic Train- Stops; and I do hereby declare the following to be a full, clear, and exact description of the invention, such as will enable others 10 skilled in the art to which it appertains to make and use the same.

The present invention relates to improvements in automatic train stops, and has for its principal object to provide an automatic 15 mechanism for turning off the steam from the locomotive cylinders, and simultaneously applying the air brakes and blowing the whistle whenever the engineer inadvertently runs past a signal set at danger.

It is another object of the present invention to provide mechanism for accomplishing these several purposes which shall be grouped together in simple arrangement, and be capable of ready actuation from a 20 trip or obstacle that is set by means of the semaphore signal.

The invention will be more particularly set out in the following description which is to be taken in conjunction with the accompanying drawings, in which similar symbols indicate like parts throughout the several views, and in which:—

Figure 1 is a side elevational view of a locomotive partly broken away, but shown 35 equipped with a mechanism constructed in accordance with the present invention;

Fig. 2 is a top plan view thereof;

Fig. 3 is a cross sectional view of the track illustrating in elevation and partly in section the signalling apparatus, and in dotted lines a part of the locomotive equipment; and

Fig. 4 is a perspective view of a device independent of the signal for operating the locomotive mechanism.

Referring more particularly to the drawings, a locomotive 1 is illustrated as traveling on a track 2, passage over which is under the control of the usual semaphore signal 3 carried on a shaft 4 in the hollow tower 5. A short length of chain 6 runs over and engages a series of pins 7 fitted in an enlarged portion 8 of the shaft within the tower 5.

The ends of the chain 6 are connected to flexible wire cables 9 and 10 which are car-

ried down within the hollow tower 5, and after being engaged about pulleys 11 and 12 respectively are directed at right angles through an opening 13 in the lower end of 60 said tower 5.

The outer ends of these wire cables 9 and 10 are coupled to the opposite ends of a chain length 14, engaging pins 15 on an enlarged part 16 of a second shaft 17, journaled close to the track 2, as shown more particularly in Figs. 2 and 3. The enlarged part 16 of the shaft 17 also movably supports an inverted L-shaped trip or obstacle 18 which, when the semaphore 3 is in the 70 danger position shown in Fig. 3, is adapted to stand upright and to engage either of a pair of arms 19 and 20 on the opposite ends of a rock shaft 21 journaled on the forward part of the locomotive 1.

This rock shaft 21 carries a segment 22, which receives at its opposite sides the divided ends 23 and 24 of a flexible wire cable 25. This cable is directed over suitable pulleys 26 and 27, and includes an elastic tension device 28. The rear divided ends 29 and 30 of the flexible cable 25 pass in opposite directions over pulleys 31 and 32, and are coupled, respectively, to the lever 33 of the air brake appliance and an arm 34 for 85 turning steam into the whistle 35.

A second arm 35 is joined to the flexible cable 25 by suitable connections 36 and 37, and such arm controls the opening and closing of a steam valve indicated at 38 in 90 Fig. 2.

The operation of the present invention may be briefly described as follows:—

When the semaphore 3 rests in the danger position shown in Fig. 3, the trip or obstacle 95 18 is in the raised position, and if, when so set, the engineer inadvertently runs past the signal either the arm 19 or 20, in accordance with the direction in which the engine is running, will strike the shaft 21 on the locomotive to be rocked in either a clockwise or counter-clockwise direction according as the engine is running in a forward or reverse direction.

This rocking of the shaft 21 will cause a draft on either one of the divided ends 23 or 24, which will result in a forward pull on the flexible cable 25. The force and jar of this pull will be absorbed in the elastic 100 tension device 28. This forward pull on the cable 25 will operate to swing the arm 35

2 through the connection 37, thereby closing the steam valve 38; while at the same time the divided rear end 29 will pull the air brake lever 33 to bleed the air line and apply the brakes, and the other divided rear end 30 will operate the arm 34, thus blowing the whistle 35. After actuation the air brake lever 33 may be drawn rearwardly to again close the system, which will draw rearwardly upon the flexible cable 25 and through the connections 36 will return the steam valve arm 35 to the initial position with the steam line open.

Of course, when the semaphore 3 is moved to the "clear track" position the shaft 4 will be actuated, turning the pins 7 which engage the chain length 6, and in turn actuate the cables 9 and 10 and opposite chain section 14 to lower the trip or obstacle 18, thus placing the same out of the path of the arms 19 and 20.

The shaft 17 preferably carries a movable stop 39, adapted to abut against a fixed stop 40 to limit the movement thereof and cause 25 the trip or obstacle 18 to take the proper position to be engaged by the arm 19 or 20.

Referring now more particularly to the device shown in Fig. 4, 41 and 42 designate members of a post which are bent from a 30 single sheet of metal having its ends 43 and 44 bent at right angles to the post to engage the upper face of a tie indicated at 45, and with its extremities forming flanges 46 and 47 for embracing the sides of the tie, and 35 having struck-in portions providing prongs for taking a firm hold of the same.

The above parts are made from spring metal in order to permit the flanges 46 and 47 to normally spread apart to a distance 40 capable of readily receiving the tie, and being afterward clamped together by a cam head 49 on one end of a revoluble shaft 50 and by a lever 51 having a cam face 52 also adapted to engage the opposite flange 47.

45 A cross bar 53 is secured in any desired manner to the post, and is adapted to be placed in such a position on the cross tie as to engage either of the arms 19 or 20 on the locomotive to actuate the same in a manner 50 similar to the trip or obstacle 18. The outer end of the cross bar 53 is rolled, as indicated at 54, to provide a socket in which is placed a red or other flag 55, and is also formed with a notch 56 in which may be hung the 55 bail of a red or other lantern 57.

This device is adapted to be carried by the brakeman on the rear end of the train, and when said train becomes stalled in the middle of a block such device is to be carried by the 60 brakeman to a suitable distance in rear of the train, where it is to be fixed to a cross tie by the operation of the lever 51 and cams 49 and 52, and the same will give a visible signal by means of the flag 55 and lantern 57, and which, if the engineer disregards,

will, through the cross bar 53, automatically actuate the locomotive appliance and bring the train to a stop.

The device is to be carried by head or rear flagmen, section crew or other employees, where it can be used in case of derailment, washout, or other accident.

The rock shaft can be carried by electric locomotive, and when connected properly to brakes on electric locomotive will bring said 75 electric locomotive to stop in the same manner as locomotive propelled by steam.

The arms 19 and 20 taper downwardly so as to be lighter at their lower ends where they come in contact with the trip 18, in order to strike an easier blow; and to further this object the trip 18 is cushioned with a piece of rubber hose 18' which prevents the two pieces which are of metal coming in direct contact.

85 Where I have specified in the claims steam locomotive and steam valve, the same are to be understood as equally well referring to an electric locomotive and its controller, to which my invention is in like manner applicable.

90 It will be obvious that various modifications might be made in the herein described construction, and in the combination and arrangement of parts which could be used, 95 without departing from the spirit of my invention.

I claim:—

1. The combination with a locomotive having a steam cut-off valve, a whistle valve, 100 and an air brake appliance, of a rock shaft journaled at the forward part of said locomotive and having its ends projecting at opposite sides thereof, tapering arms depending from said rock shaft and adapted to oscillate same when said arms are struck by an obstacle, a segment carried by and turning with said rock shaft, a flexible cable having divided forward ends connected to opposite parts of said segment whereby the cable may be drawn forwardly when said rock shaft is oscillated in either direction; a connection between said cable and steam valve for closing the same when the cable is pulled forwardly and connections between said cable, whistle valve and air brake appliance for actuating same when the cable is drawn forwardly, substantially as described.

110 2. The combination with a locomotive having a steam cut-off valve, a whistle operating valve and an air brake appliance, of a rock shaft journaled in the forward part of said locomotive and having its ends projecting beyond both sides of the locomotive, 115 tapering arms fastened on the projecting ends of said shaft and adapted to be struck by an obstacle along the roadway whereby to oscillate said shaft, a segment held to move with said shaft, a flexible cable, for- 120 125 130

- ward divided strands on one end of said cable connected to opposite parts of said segment for drawing the cable forwardly when the rock shaft is oscillated in either direction, a connection between said steam valve and cable whereby to close the former when the latter is pulled forwardly, divided strands at the rear end of said cable, one of said strands being connected to open the 10 whistle valve when the cable is pulled forwardly, the other of said strands being connected to actuate the air brake appliance for applying the brakes when the cable is moved forwardly, substantially as described.
- 15 3. The combination with a locomotive having a steam cut-off valve, whistle valve, and air brake appliance, of a cable fitted on the locomotive, means whereby the cable may be drawn forwardly, a shock absorption device included in said cable, a connection whereby said steam valve may be closed when the cable is drawn forwardly, a second connection whereby the steam valve may be opened when the cable is drawn rearwardly, divided strands connected to the rear end of said cable, one of said strands being connected to actuate the whistle valve when the cable is drawn forwardly, the other of said strands connected to the air 50 brake appliance for actuating same to apply the brakes when the cable is moved forwardly, substantially as described.
- 20 4. The combination with a locomotive having a steam cut-off valve, whistle valve, and air brake appliance, of a rock shaft journaled in the forward part of said locomotive, arms on said rock shaft adapted to encounter an obstacle whereby to oscillate the shaft, a flexible cable, means whereby said cable may be drawn forwardly when the rock shaft is swung in either direction, a connection for closing the steam cut-off 55 valve when the cable is drawn forwardly, a second connection for opening the steam cut-off valve when the cable is returned rearwardly, and means for opening said whistle valve and bleeding the air line through said air brake appliance when the cable is drawn forwardly, substantially as described.
- 25 5. The combination with a locomotive having a steam cut-off valve, whistle valve, and air brake appliance, of a cable fitted on the locomotive, means whereby the cable may be drawn forwardly, a connection between the cable and steam valve for closing the latter when the cable is drawn forwardly, a connection between said cable and steam valve for returning said valve to the open position when the cable is moved rearwardly, and connections between said cable, whistle valve and air brake appliance for actuating the same when the cable is drawn forwardly, substantially as described.
- 30 6. The combination with a locomotive having a steam cut-off valve, whistle valve, and air brake appliance, of a cable fitted on the locomotive, means whereby the cable may be drawn forwardly, a shock absorption device included in said cable, a connection whereby said steam valve may be closed when the cable is drawn forwardly, a second connection whereby the steam valve may be opened when the cable is drawn rearwardly, divided strands connected to the rear end of said cable, one of said strands being connected to actuate the whistle valve when the cable is drawn forwardly, the other of said strands connected to the air 60 brake appliance for actuating same to apply the brakes when the cable is moved forwardly, substantially as described.

In testimony whereof, I affix my signature.

ELIJAH BESS.
